UNITED STATES PATENT OFFICE.

PETER BROADBOOKS, OF BATAVIA, NEW YORK.

COMBINED WIRE-SHEARS AND PARALLEL-JAW PLIERS.

SPECIFICATION forming part of Letters Patent No. 611,102, dated September 20, 1898.

Application filed October 8, 1897. Serial No. 654,539. (No model.)

To all whom it may concern:

Be it known that I, PETER BROADBOOKS, a citizen of the United States, residing at Batavia, in the county of Genesee and State 5 of New York, have invented a certain new and useful Improvement in Combined Wire-Shears and Parallel-Jaw Pliers, of which the following is a specification.

My invention relates to a new and useful 10 improvement in combined wire-shears and parallel-jaw pliers, and has for its object to so construct such a device that the pliers shall add great strength and durability to the wire-shears; and a further object of my in- 15 vention is to produce a device of this description which shall be exceedingly simple in construction and efficient in action.

With these ends in view this invention consists in the details of construction and com- 20 bination of elements hereinafter set forth and then specifically designated by the claims.

In order that those skilled in the art to which this invention appertains may understand how to make and use the same, the construction and operation will now be described 25 in detail, referring to the accompanying drawings, forming a part of this specification, in which—

Figure 1 is a side elevation of a pair of parallel-jaw pliers having my improvement combined therewith, the device being closed; Fig. 2, a similar view, the jaws being open and a portion of the handles being broken away; Fig. 3, a dismembered perspective view 35 of the device, showing the several parts which together make up my improvement; Fig. 4, a view similar to Fig. 1, but showing an addition thereto of a punch. Fig. 5 illustrates the embodiment of my improvement in a pair 40 of cut-off pliers; Fig. 6, a detail section of pivoting-stud; and Fig. 7 is a top plan view of the form shown in Fig. 4, the handles being broken away.

In carrying out my invention as shown, A 45 and B represent the handles of a pair of pliers, which are let together and pivoted at C, the circular heads being cut away, as indicated at D, for the purpose hereinafter set forth.

E and F are the parallel jaws, which are 50 pivoted directly to the levers at G, and these jaws are slotted at the rear, so as to provide the shanks H, which embrace the heads of

the levers and are pivoted thereto by means of the studs I, said studs being set in the handle-levers, so as to revolve therein, and 55 are flattened at the points extending through the slots J, formed in the shanks, the object of which is to present a comparatively large bearing-surface between these studs and the walls of the slots and permit the flattened 60 sides of the studs always to lie parallel with the side walls of the slots, as will be readily understood. This arrangement forms an exceedingly rigid joint between both the levers and the parallel jaws, thus preventing the 65 twisting of either said levers or jaws when in use, and this is an important feature of my improvement, since heretofore the sidewise strain brought to bear upon pliers and cutters, spring and twist the same to such an extent as to often result in the breaking thereof. 70

Cutters K and L may be secured or formed with the parallel jaws E and F, respectively, and so arranged that they will serve as cut-offs for wire and the like, and it is to be noted 75 that these cutting-jaws are close to the center fulcrum while the tool is open, so that when said jaws enter into the metal to be cut the cutters travel or draw away from said fulcrum and the distance between said fulcrum and 80 the cutters is greater, so that a wire may be set against the head of the levers and be cut without the least outward strain on the cutters, thus obviating the wedging in of the piece cut between the cutters and the head of 85 the levers. The shanks of the parallel jaws lying in close contact with and covering nearly the whole surface of the lever-heads, which are pivoted substantially, they are not liable to strain or twist by the pressure. 90

The cut-away portion D of the lever-heads is for a better accommodation of the wire or other article to be operated upon by the cutters K and L. Cut-off dies M may be formed in the rear portion of the heads of the levers 95 and be utilized for severing small wire rods.

In Fig. 4 I have shown embodied with the construction just described an overhanging arm N, pivoted between the shanks of the jaw E by means of the pin G, which also pivots the jaw to the handle, said jaw E being slotted just a little farther forward in this construction than in the first-described form. A rearwardly-projecting extension X is formed on 100

the arm N and bears against the rounded edge of the lever A, with which it is arranged eccentrically, as shown in dotted lines in Fig. 4, whereby it will be understood that when the 5 jaws are pressed together the rounded edge will press against the extension X and cause it to operate the lever N, on the forward end of which is a punch O, working in the die P, formed on the upper jaw. It has been found 10 that this combination is advantageous and that a most powerful punch relative to the capacity of the implement is thereby provided. The cut-off pliers shown in Fig. 5 consists of the handle-levers Q, which are pivoted together at R and have pivoted thereto at S the 15 cut-off jaws T, the shanks of said jaws being slotted and pivoted to the handle-levers by the studs U, with the same result as that just described, these jaws terminating in the cutting edges V in the usual manner. Cut-off 20 dies W may be formed in both the front and rear of the heads of the levers for the usual purpose. It is to be noted that in this construction the jaws cannot twist, because they 25 move in a direct line to each other and have more room, so that a wire may be placed nearly to the center of the cutter.

Of course I do not wish to be limited to the construction here shown and described, as 30 these details may be varied to a considerable extent without departing from the spirit of my invention, and the device may be utilized for other tools than those here set forth.

Having thus fully described my invention, 35 what I claim as new and useful is—

1. In a pair of pliers, two levers pivoted together, parallel jaws having slotted shanks

embracing said levers, said jaws being pivoted to the levers and also connected thereto by movable studs operating in slots, and cut-off 40 jaws carried by the first-named jaws, as specified.

2. In combination, a pair of handle-levers let together and pivoted to each other, a pair of parallel jaws, slotted shanks formed therewith adapted to embrace the levers, said jaws being pivoted to the front portion of said levers, revolving studs set in the levers and having flattened portions projecting through slots formed in the shanks of the jaws, cut-off 45 dies carried by the heads of the levers, and cutters carried by the parallel jaws, as shown and described.

3. In combination with a pair of pliers of the character described, an overhanging arm 55 formed with one of the handle-levers, and a die carried by one of the parallel jaws, substantially as and for the purpose set forth.

4. A pair of pliers consisting of two levers, plier-jaws hinged thereto and means for holding 60 said jaws parallel with each other when the levers are operated.

5. A pair of pliers consisting of two levers, jaws pivoted thereto having slotted shanks, and studs on the levers projecting through 65 said slots, as and for the purpose described.

In testimony whereof I have hereunto affixed my signature in the presence of two subscribing witnesses.

PETER BROADBOOKS.
